UNITED STATES PATENT OFFICE.

LEE O. GARRAWAY, OF MEMPHIS, TENNESSEE.

PREHEATER ATTACHMENT FOR BOILERS.

Application filed October 16, 1924. Serial No. 744,091.

The present invention relates to an attachment for boilers adapted to preheat the feed water before entering the boiler.

The object of the present invention is to provide an attachment for boilers which will heat the water twice and for this purpose use the exhaust steam which is generally wasted, and the invention is equally well suited for engines equipped with lifting or non-lifting injectors or pumps or any other means for supplying water to the boiler.

In the accompanying drawings:

Figure 1 is a side elevation of a modern locomotive with some parts removed and my heater attachment employing a non-lifting injector installed;

Fig. 2 is a transverse section on the line 2—2 of Fig. 1;

Fig. 3 is a section on the line 3—3 of Fig. 1;

Fig. 4 is a detail partly in section and partly in plan of a circulating coil;

Fig. 5 is a section on the line 5—5 of Fig. 1;

Fig. 6 is a detail section on the line 6—6 of Fig. 1.

Fig. 7 is a detail showing the connection between the initial heating tank and the main supply tank.

In the drawings, the reference numeral 10 represents a locomotive of any modern type 38 provided with a cylinder saddle 11 and a smoke box 12. The reference numeral 13 designates the water intake port to the boiler and the numeral 14 denotes a circulating coil for the feed water which makes several turns in the heater casing 15 so as to heat the water on its way to the boiler intake port 13. The coil 14 is a part of the water feed pipe 16 which extends from the non-lifting injector 17 and is equipped with the boiler check valve 18. The heater casing 15 extends longitudinally upon the side of the boiler near the top thereof, and the front end of the coil extends from the casing, as at 19, to the intake port 13. 20 is the usual live steam intake pipe and 21 is the overflow pipe. The exhaust steam escaping from the cylinder saddle passes through an oil separating device 22 which is mounted upon the rear end of the saddle and has one or more perforated

50 metallic plates 23 (see Figs. 2 and 6) covered with an oil absorbing cloth or fabric 24 of any approved texture. The oil absorbing fabric is caused to completely encase the metallic plate and the covered plate is then 55 slid into engagement with cleats or grooves, indicated at 25, and the outer side of the oil

separator is removable to facilitate washing out the heater and removing the oil absorbing cloth for washing out the oil. The exhaust steam passes through the oil separating contrivance and is then led by a pipe 26 and branches 27 into the front ends of the heater casings 15 which are provided one on each side of the boiler. From the rear end of each said casing, a pipe 28 leads into the tank 29 which is fed from the supply tank 30 through a hose 31 and a pipe 32, and 33 is a pipe leading the heated water from the tank 29 into the injector 17. As will be understood on reference to Figs. 1 and 5, the tank 29 extends across beneath the frame of the engine and connects the feed pipes on the opposite sides thereof.

34 and 35 are controlling rods passing up into the cab to permit the closing or opening, at will, of the water inlet valve to the injector and the overflow valve, respectively.

36 designates the ports or passages through which the exhaust steam enters the oil separators.

In the heater 15, I propose to make several turns of the pipe 14, as shown by Figs. 1 and 4 of the drawings, or use a series of pipes for the water to travel through on its way to the boiler. The heater casing 15 is placed on top 85 of the asbestos lagging 37 which covers the boiler, and beneath the jacket 38, (see Fig. 3).

The operation of the preheater attachment is as follows: The exhaust steam is taken from the exhaust cavities, and when the throttle valve is opened the exhaust steam will back up from the exhaust cavities through the apertures 36 in the cylinder saddle and then flow through the oil separators and the pipe 26 into the main heater casing 15, flowing around the coil 14 and heating the water in the coil. This forms the main heating stage of the water. From the heater casing 15, the exhaust steam is led by the pipe 28 into the heating and condensation tank 29 where the heat from the steam is imparted to the water and the steam is condensed in the water to return to the boiler. This forms the first heating stage of the water.

When in the claims the term "conduit" for the exhaust steam and condensate is used, this is meant to include the pipe 26, the casing 15, oil separator 22 and pipe 28. In other words, it includes the entire passage for the exhaust steam and condensate from the cylinder saddle to the injector.

It is to be understood that the casing or

heater 15 may be omitted and the pipe 26 coupled directly to the pipe 28.

Having thus described the invention, I claim:

- 5 1. A feed water heater system for locomotives comprising a tank arranged below the fire box and in rear of the locomotive boiler and receiving water by gravity from a source of supply, a casing secured upon the boiler and extending longitudinally thereof, a water coil within the casing extending longitudinally thereof, a pipe extending from the front end of the water coil into the water space of the boiler, a connection between the rear end 10 of the water coil and the outlet of the tank, means in said connection for causing flow of water from the tank through the water coil into the boiler, means in said connection preventing flow from the boiler to the tank, a 15 conduit leading exhaust steam from the locomotive engines into the front end of the casing, and a conduit leading exhaust steam from the rear end of the casing and delivering said exhaust steam into the water in the tank 20 to be condensed therein.

2. A feed water heater system for locomotives comprising a tank disposed below the cab of the locomotive and connected with a source of water supply, a casing secured upon and extending longitudinally of the shell of the locomotive boiler near the top thereof, a pipe extending around the smoke box of the boiler and connecting the front end of the casing with the exhaust of the locomotive engines, a pipe connecting the rear end of the casing with the tank and discharging into the tank, a water coil within the casing effecting flow of water back and forth along the top portion of the shell of the boiler, a pipe leading from the front end of the water coil into the water space of the boiler, a water-forcing device in front of the tank and connected with the outlet of the same, a pipe connecting the outlet of the water-forcing device with the rear end of the water coil, and a check valve being interposed in said pipe to prevent flow toward the water-forcing device.

In testimony whereof I affix my signature.

LEE O. GARRAWAY. [l. s.]
